L. H. DAVIS

ENGINE STARTING APPARATUS

Filed Jan. 12, 1926

Patented Aug. 9, 1927.

UNITED STATES PATENT OFFICE.

LEWIS H. DAVIS, OF ANDERSON, INDIANA, ASSIGNOR, BY MESNE ASSIGNMENTS, TO
DELCO-REMY CORPORATION, OF DAYTON, OHIO, A CORPORATION OF DELAWARE.

ENGINE-STARTING APPARATUS.

Application filed January 12, 1926. Serial No. 80,757.

This invention relates to apparatus for starting internal combustion engines and particularly to the type of apparatus which includes a motor, a pinion driven by the motor and movable endwise into engagement with the gear of an engine to be started, and a one-way clutch for connecting the pinion with the motor so that the pinion may overrun the motor shaft when the engine becomes self-operative.

It is an object of the present invention to simplify the construction and improve the operation of the overrunning clutch referred to. To this end, the invention provides a clutch comprising two coaxial clutch drums one of which is connected with the pinion and the other with the motor, and a helical spring normally engaging the drums with relatively little friction, the spring being stressed into driving engagement with the drums, when either of the drums is rotated in a certain direction. In this manner the motor is automatically connected with the engine when it tends to drive the engine after the pinion is engaged with the engine gear, and the pinion overruns the motor when the engine becomes self-operative. The drum connected with the pinion is radially yieldable into engagement with a third drum connected with the motor, so that, when the spring is stressed against the pinion drum, the pinion drum will be forced into driving engagement with said third drum.

Further objects and advantages of the present invention will be apparent from the following description, reference being had to the accompanying drawings, wherein a preferred form of embodiment of the present invention is clearly shown.

In the drawings:

Figs. 1 and 2 are fragmentary side views partly in section of the form of starting apparatus embodying the present invention.

Fig. 1 shows the apparatus disconnected from the engine, and Fig. 2 drivingly connected with the engine.

Fig. 3 is a sectional view on line 3-3 of Fig. 1.

Fig. 4 is a sectional view on line 4-4 of Fig. 3.

Fig. 5 is a sectional view on line 5-5 of Fig. 4.

Referring to the drawings, numeral 20 designates the field frame of an electric motor, the frame being attached to a gear housing 21 adapted to be supported by the frame of the engine to be started. The engine is not shown but is represented by a flywheel gear shown in fragment at 22. The field frame 20 and the housing 21 support an armature shaft 23 having a splined portion 24 which is engaged by the splines 25 of a sleeve 26 which is slideable along the shaft 24. The sleeve 26 is provided with a drum portion 27 coaxial with a drum member 28 provided by the hub of a pinion 29 having teeth 30 for meshing with the gear 22. The drum 28 is normally out of driving engagement with a drum 31 provided by the sleeve 26, but is divided by notches 32 into resilient segments 33 which can move radially into driving engagement with the drum 31. A helical coil clutch spring 34 is normally non-drivingly connected with the drums 27 and 28 but bears against them with light frictional pressure. A tube 35 is attached by a screw 36 to a flange 37 of sleeve 26 and has a flange 38 which engages a washer 39 carried by the pinion 29. Thus the spring 34 is enclosed and the sleeve 26 and pinion 29 are kept assembled. Movement of the pinion 29 relative to the sleeve 26 toward the right may be limited also by a pair of half-washers 38^a which are received by a groove 39^a in the sleeve 26 and by a suitable recess in the hub of the pinion 29. These half-washers are retained by a wire split ring 40 located in the groove 39^a.

The mechanism for moving the sleeve 26 endwise comprises a pedal 41 movable through a cup-shaped washer 42 attached to the floorboard 43 of an automobile. A spring 44 maintains the pedal in the upper position as shown in Fig. 1. The pedal 41 is attached to a pedal lever 45 which is mounted on a rod 46 supported by the housing 21. The lower end of lever 45 carries a rod 47 which is received by a slot 48 provided in the stem portion 49 of a block 50 which is T shaped in plan view as shown in Fig. 5. The block 50 is attached to two studs 51 which extend

through holes 52 (see Fig. 4) in the yoke 53 of a bifurcated lever 54 which is also pivotally supported by the rod 46. Each stud 51 carries a washer 55 and is surrounded by spring 56 which is located between the washer 55 and the yoke 53. The springs 56 are initially compressed so as to maintain the T shaped block 50 in engagement with the lever yoke 53. The lower ends of the lever 54 are received by a groove 57 which is provided between the flange 37 and a washer 58 attached to the sleeve 26. The spring 44 acting through the pedal 41, pedal lever 45, block 50 and lever 54 causes the sleeve 26 to be maintained normally in contact with a stop member 59 provided by the shaft 23.

The lever 45 carries a screw 60 maintained in adjusted position by lock nut 61. The screw 60 engages the plunger 62 of a motor switch which is enclosed by a switch case 63 attached by screw 64 to the motor frame 20. The switch case 63 encloses stationary contacts, one of which is attached to the motor field winding and the other to a terminal 65 which is adapted to receive a wire leading from a storage battery or other current source. The case 63 encloses also a movable contact attached to the lower end of the plunger 62. A spring 66 is located between the switch case 63 and a cap 67 attached to the plunger 62 and normally maintains the plunger in switch-open position.

To start the engine the operator presses the pedal 41 to cause the lever 45 to move from the position shown in Fig. 1 to that shown in Fig. 2. Provided the pinion teeth 30 do not abut the teeth of the flywheel gear 22, the pinion 29 will be moved into mesh with the engine gear before the motor is caused to operate by the closing of the motor switch which occurs when the screw 60 engages the plunger 62 and moves it into the position shown in Fig. 2. When the motor switch is closed the shaft 23 will rotate in the direction of the arrow 70 and will cause the sleeve 26 to be rotated in the same direction. Since the pinion 29 is prevented from rotating by its engagement with the gear 22, the spring 34 will tend to remain stationary due to the friction between it and the pinion clutch drum 28. Friction between the spring 34 and the drum 27 will cause the spring 34 to be constricted into driving engagement with the drums 27 and 28. The constriction of the spring 34 around the drum 28 causes its segments 33 to be squeezed into driving engagement with the third drum 31 provided by the sleeve 26. Thus the motor is drivingly connected with the pinion through the drums 28 and 31 as well as through the drum 27, spring 34 and drum 28.

When the engine becomes self-operative, it will rotate the pinion 29 faster than the pinion can be rotated by the motor, therefore

the pinion will become a member tending to drive the motor. This condition will tend to cause the spring 34 to be unwound so that its convolutions will increase in diameter and therefore be released from driving engagement with the clutch drums 27 and 28. Therefore, the pinion 29 will overrun the sleeve 26 and the motor shaft will not be driven by the engine.

When the operator releases the pedal 41, the spring 44 will operate to withdraw the pinion 29 from engagement with the engine gear. The release of the pedal 41 also permits the switch plunger 62 to return to switch-open position.

In case abutment should occur between the teeth 30 of the pinion and the teeth of the flywheel gear 22, the springs 51, which provide a yielding connection between the levers 45 and 54, will permit the lever 45 to be moved into the position shown in Fig. 2 to close the motor switch in order that the shaft 23 may be rotated to cause the pinion 29 to be rotated into registry with the engine gear 22. When this occurs, the springs 51 which will have hitherto been compressed beyond their initial state of compression, will be released to cause the sleeve 26 and parts carried thereby to be moved quickly toward the right so as to move the pinion into engagement with the engine gear.

While the form of embodiment of the present invention as herein disclosed, constitutes a preferred form, it is to be understood that other forms might be adopted, all coming within the scope of the claims which follow.

What is claimed is as follows:

1. Engine starting apparatus comprising, in combination, a motor; a pinion driven by the motor and movable into mesh with a gear of the engine to be started; and a one-way clutch for connecting the pinion and motor and comprising aligned clutch drums connected respectively with the motor and pinion, a helical coil spring normally in light frictional engagement with said drums and adapted to drivingly connect the drums when either drum is rotated in a certain direction, and a third drum connected with the motor and located concentrically to and substantially coextensive with the pinion drum, the pinion drum including radially displaceable segments which are forced into driving engagement with the third drum when the spring drivingly connects the first mentioned drums.

2. Engine starting apparatus comprising, in combination, a motor; a pinion driven by the motor and movable into mesh with a gear of the engine to be started; and a one-way clutch for connecting the pinion and motor and comprising aligned clutch drums connected respectively with the motor and pinion, a helical coil spring encircling the

drums and normally in light frictional engagement with said drums and adapted to drivingly connect the drums when either drum is rotated in a certain direction, and a 5 third drum connected with the motor and located within the pinion drum, the pinion drum including radially displaceable segments which are forced into driving engagement with the third drum when the spring 10 drivingly connects the first mentioned drums.

3. Engine starting apparatus comprising, in combination, a motor; a shaft driven by the motor; a sleeve slidable along the shaft 15 and driven thereby, a pinion normally freely rotatable upon said sleeve; a one-way clutch for connecting the shaft and pinion and comprising aligned drums provided by the sleeve and pinion, respectively, a helical coil 20 spring normally in light frictional engagement with said drums and adapted to drivingly connect the drums when either drum is rotated in a certain direction, and a third drum provided by the sleeve and located concentrically to and substantially coextensive 25 with said pinion drum, the pinion drum including radially displaceable segments which

are forced into driving engagement with the third drum when the spring drivingly connects the first mentioned drums; and means 30 for moving the sleeve endwise.

4. Engine starting apparatus comprising, in combination, a motor; a shaft driven by the motor; a sleeve slidable along the shaft 35 and driven thereby, a pinion normally freely rotatable upon said sleeve; a one-way clutch for connecting the shaft and pinion and comprising aligned drums provided by the sleeve and pinion, respectively, a helical coil spring 40 encircling the drums and normally in light frictional engagement with said drums and adapted to drivingly connect the drums when either drum is rotated in a certain direction, and a third drum provided by the sleeve and located within the pinion drum, the pinion drum including radially displaceable segments which are forced into driving 45 engagement with the third drum when the spring drivingly connects the first mentioned drums; and means for moving the sleeve 50 endwise.

In testimony whereof I hereto affix my signature.

LEWIS H. DAVIS.
